(57) **CLAIM**

We claim the ornamental design for a media device, substantially as shown and described.

DESCRIPTION

FIG. 1 is perspective view of a media device showing our new design;

FIG. 2 is a front view for the media device.

FIG. 3 is a rear view for the media device.

FIG. 4 is a top view for the media device.

FIG. 5 is a bottom view for the media device.

FIG. 6 is a right side view for the media device; and,

FIG. 7 is a left side view for the media device.

The surfaces of the media device as shown in FIGS. 1-7 are illustrated at least partially with color designations. The front surface is white, excluding the rectangular feature (e.g., display) shown with shading and the circular feature (e.g., input device) shown as gray. The back surface is metallic steel, silver, nickel or chrome. The side surfaces are divided between white and metallic steel, silver, nickel or chrome.

The broken lines are for illustrative purpose only and form no part of the claimed design.
